UNITED STATES PATENT OFFICE.

CLARENCE DULL, OF SWAMPSCOTT, MASSACHUSETTS.

DESIGN FOR A PAPER CUTTER.

Application filed December 1, 1925. Serial No. 15,596. Term of patent 7 years.

To all whom it may concern:

Be it known that I, CLARENCE DULL, a citizen of the United States, and residing at Swampscott, in the county of Essex and State of Massachusetts, have invented a new, original, and ornamental Design for a Paper Cutter, of which the following is a specification, reference being had to the accompanying drawing, forming part thereof.

Referring to the drawing:

Fig. 1 illustrates a front view of the paper cutter; and

Fig. 2 is a side view of the same.

What I claim is:

The ornamental design for a paper cutter, as shown.

In witness whereof, I hereunto subscribe my name this 19th day of November, A. D. 1925.

CLARENCE DULL.
